United States Patent Office.

JACOB D. VREDENBURGH, OF CHICAGO, ILLINOIS.

Design No. 4,824, dated April 18, 1871.

DESIGN FOR SHOW-CASES.

The Schedule referred to in these Letters Patent and making part of the same.

To whom it may concern:

Be it known that I, JACOB D. VREDENBURGH, of Chicago, in the county of Cook and State of Illinois, have invented and produced a new and original Design for Counter Show-Cases, of which the following is a specification.

The accompanying drawing is a perspective of my design for a hexagonal counter show-cases, its nature being fully represented in the illustration, to which reference is made.

What I claim, and desire to secure by Letters Patent, is—

The design for a hexagonal or six-sided prismatical show-case, as shown.

JACOB D. VREDENBURGH.
